WILL OF SAID JAMES F. DORAN, DECEASED

HAT IRONING MACHINE OR THE LIKE

Application filed January 29, 1927. Serial No. 164,393.

This invention relates to hat ironing machines or the like.

One of the objects of the invention is to provide a machine for ironing, or performing other operations upon the crown portions of hats, which is practical and highly efficient. Another object is to provide a machine of the above nature which is capable of turning out a high grade of work in a rapid and thorough manner. Another object is to provide a machine of the above nature which is capable of a wide range of use and which is conveniently adjustable to meet varying conditions found in practical operation. Another object is to provide a machine of the above nature which is capable of performing consistently even and uniform work upon the hats. Another object is to provide a machine of the above nature which operates uniformly upon all portions of the hats. Another object is to provide a machine of the above nature which is strong and rugged and capable of giving long dependable service. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which is shown one of the various possible embodiments of this invention,

Figure 1 is a top plan view of the machine;
Figure 2 is a side elevation;

Figure 3 is a section taken substantially along the line 3—3 of Figure 2;

Figure 3a is a diagrammatic view of a preferred electric wiring and switch mechanism;

Figure 3b shows diagrammatically the switch in four different positions;

Figure 4 is a detail view of a portion of a cam and a follower shown in Figure 2;

Figure 5 is a front elevation of a mechanism which is actuated by the cam of Figure 4;

Figure 6 is a side elevation of the upper

portion of the machine, viewed from the side opposite to that viewed in Figure 2;

Figure 7 is a diagrammatic view of a modified means for heating the ironing tool;

Figure 8 is a longitudinal vertical section through the head of the machine, showing the hat supporting and rotating mechanism;

Figure 9 is a front view of a portion of the plate appearing at the left-hand end of Figure 8;

Figure 10 is a section taken substantially along the line 10—10 of Figure 8;

Figure 10a is a perspective view of an attachment to be employed when hats of very low crown are being operated upon;

Figure 11 is a section taken substantially along the line 11—11 of Figure 10;

Figure 12 is a section taken substantially along the line 12—12 of Figure 8;

Figures 13, 14 and 15 are diagrammatic top plan views showing the ironing tool operating upon a hat at different points in its path of traverse;

Figure 16 is a front elevation of the machine;

Figure 17 is a detail of the iron and its supporting mechanism;

Figure 18 is a top plan view, partly broken away; showing the arms which carry and move the iron across the hat, and

Fig. 19 is a detail of a portion of one of the arms which is broken away in Figure 18.

Similar reference characters refer to similar parts throughout the several views of the drawings.

Referring now to Figures 1 and 2 of the drawings in detail, this machine is supported upon a suitable base which may be of any desired construction and of a suitable height, the base being shown in this instance as comprising what may be termed a table 20 supported by legs 21 which are suitably braced by cross pieces 22. Extending upwardly from the table 20 is a frame 23 of any suitable construction having at its upper end bearings for rotatably supporting a shaft 24. This shaft 24 may be driven by any suitable means, but is preferably driven by an electric motor 25. This motor is mounted upon the frame 23 at the rear of the machine and is connected

5 by suitable reduction gearing to drive the shaft 24. The gearing in this instance is shown as a worm wheel 26 mounted upon the armature shaft of the motor and driving a worm wheel 27 which is secured to the rear end of the shaft 24. About these gears is a casing 28 which encloses the gears together with the armature shaft of the motor and the rear end of the shaft 24 and which may be 10 filled with grease or oil to insure proper lubrication of these parts.

15 The shaft 24 is thus driven from the motor 25 at greatly reduced speed, the speed of rotation being that suitable for rotating a hat while the hat is being ironed or while other operations are being performed upon the crown thereof. The shaft 24 rotates a hat block shown at 29 in Figure 2 and carrying a hat body 30, the hat block being rotated at 20 the speed of rotation of the shaft 24 through a mechanism which will be described in detail presently.

25 Referring still to Figures 1 and 2, there is shown adjacent to the hat 30 a tool 31 which is adapted to operate upon the crown portion of the rotating hat. This tool 31 is shown herein as a heated ironing tool since certain parts of the mechanism hereinafter described achieve certain distinct practical advantages when employed in this particular 30 operation of ironing hat bodies, but it is to be understood that not all of the features of this machine are limited in their use to an ironing operation. This ironing tool is 35 adapted to be urged against the surface of the hat body 30 by suitable means such as a suspended weight 32, and, by means of mechanism which will be described presently, the iron is moved in a horizontal path of traverse 40 across the surface of the rotating hat. This path of traverse extends between the band and tip of the hat and, as will be described, the iron may be made to travel from the band on one side of the rotating hat to the band on 45 the opposite side or between any two intermediate points.

50 As shown in Figure 2, there is secured to the shaft 24 near the middle portion thereof a worm gear 33. This worm gear drives a worm wheel 34 which is preferably positioned directly beneath the shaft 24 and which is rotatably supported in an arm 35. This supporting arm 35 is pivoted to the frame 23 at its rear end 36 so that the worm wheel 34 may be lowered and moved out of driving 55 engagement with the worm gear 33. The front end of the supporting arm 35 is held up by a cam 37, this cam being manually rotatable to permit the worm wheel to drop out of engagement with the worm. The cam 37 is manually controlled by a handle 38 which is on the side of the frame 23 opposite to the cam 37 and which is shown in Figure 6. As shown in Figure 2, there is provided 60 a pin 39 against which the cam 37 moves as

it is rotated by the handle 38 to permit the worm wheel to drop. This pin 39 limits the downward movement of the arm 35 and of the worm wheel and supports the weight of these parts when the worm wheel 34 is out of driving engagement with the worm gear 33.

65 In the position of the parts shown in the drawings, the worm wheel 34 is in its uppermost position, in driving engagement with the worm 33. As best shown in Figure 6, there is connected to the worm wheel 34 a link or crank 40. The connection is made by a bolt 41 in the crank arm 40 engaging a radial slot 42 in the worm wheel. The crank arm 40 is pivotally connected at its forward end 43 to an upstanding bracket 44 which is clamped to a sliding rack 45 by means of set screws 46. The rack is slidably supported in suitable brackets 47 and 48.

70 As the worm wheel 34 is slowly rotated by the worm 33 the crank arm 40 reciprocates the rack 45. The length of these reciprocations may be varied by adjusting the bolt 41 in the radial slot 42 toward or away from the center of the worm wheel. The worm wheel is preferably counter-weighted, as shown at 75 49 in Figure 6, so that the machine will not stop with the crank arm 40 on dead center.

80 Referring now to Figures 2 and 3, the front 85 end portion of the rack 45 engages with a gear 50 which is fixed upon a hollow vertical spindle 51, this spindle 51 being rotatably mounted at the outer end of a forwardly projecting bracket 20a of the frame. This spindle 51 is a part of an outwardly projecting arm 52 which is thus adapted to be swung about the axis of the spindle 51 by the reciprocating rack 45. The mounting of the spindle 51 in the bracket 20a is preferably 90 through ball bearings 53 and 54 so that the arm 52 is capable of swinging with maximum 95 freedom.

100 As shown in Figure 1, there is pivotally connected to and supported by the arm 52 at its outer end 55 another horizontal arm 56. At the outer end of this last arm 56 the iron 105 31 or other tool is mounted and supported as will be described in detail. As may be seen in Figure 2, the weight 32 is suspended preferably by a chain 57 which passes upwardly through the hollow spindle 51 (Figure 3) and over a roller 58. From the roller 58 the chain passes outwardly and is connected adjacent the outer end of the arm 56. This latter connection will be described in detail hereinafter. The weight 32 thus tends to swing the arm 56 about its pivot 55 to carry the iron 31 into engagement with the hat crown and to urge the iron against the surface of the felt. The 110 rack 45 acting through the gear 50 and driven from the worm wheel 34 turns the arm 52 about the axis of the spindle 51 and causes the iron to move in a horizontal path of 115 traverse across the surface of the rotating hat.

In the drawings, the iron is shown held away from engagement with the hat against the action of the weight 32. This is accomplished preferably by a pin 58^a which may be seen in Figure 1 adjacent to the pivot 55. This pin is shown also in Figures 2 and 6. It is carried in vertical hole in a projection 59 of the arm 56 and is adapted to drop by gravity or other suitable means into a hole in a ledge 60 which projects outwardly from the arm 52. To permit the tool to move into engagement with the hat under the urge of the weight 32, the pin 58^a is simply lifted out of the hole in the ledge 60 and, while the machine is in operation, the lower end of the pin is supported by the ledge 60. When the tool is manually drawn back from the hat by swinging the arm 56 around its pivot 55 against the action of the weight 32, the pin drops by gravity or any suitable means into the hole in the ledge 60 and thereafter holds the iron in its inoperative position.

As shown in Figure 3, the roller 58 over which the chain 57 passes is preferably mounted in a housing 61, and this housing 61 has a hollow downward extension 62 which registers with the end of the hollow spindle 51 and which is swiveled in the arm 52. The chain passes out of the housing 61 through a restricted mouth 63 to the iron. Thus, as the iron moves in its path of traverse over the hat, the housing 61 is permitted to turn about its upright axis and the axis of the roller 58 is always kept in proper position for permitting free movement of the chain 57 and proper transmission of the pull of the weight 32 to the iron without binding or friction. This insures that the pressure of the iron against the hat will be uniform throughout the path of traverse of the iron. The weight 32 is provided with removable sections 32^a so that the pressure with which the iron is urged against the surface of the felt may be adjusted.

Considering now the mounting of the iron 31 upon the outer end of the arm 56, as shown in Figure 19 the end portion of this arm is provided with a substantially right angular extension 56^a. Adjacent this right angle bend in the arm 56, at 64, there is swiveled in the arm an upright spindle 65, as shown in Figure 17. This spindle 65 is fastened by a pin 66 to an iron supporting frame 67 which carries the iron 31. At the outer end of the part 56^a is clamped an upright tubular part 68. At the upper end of this tubular part or pipe 68 is an arm or bracket 69 which extends substantially parallel to the part 56^a and in which is rotatably supported the upper end 67^a of the iron supporting member 67. The iron 31 is thus mounted upon the arm 56 to swivel about a vertical axis passing through the opening 64 in the arm, that is, the supporting member 67 carrying the iron may swivel about a vertical axis.

The spindle or pin 65 passes downwardly through the opening 64 in the arm 56 and has secured to the lower end thereof, as by a set screw 70, an arm 71. This arm 71, as shown in Figures 17 and 18, is pivotally connected at 72 with an arm 73, this arm 73 being pivotally connected at 74 with a member. This member 75 is substantially in the shape of a bell crank lever, being pivoted upon the lower end of the pipe 68 and having a short arm 76. A collar 77 about the pipe 68 below the lever 75 holds the lever in place about the pipe. The chain 57 passing to the weight 32 is connected to the short arm 76 of the bell crank lever. The four members 56^a, 71, 73 and 75 constitute a parallel linkage mechanism, the axes of the pivots for these members being so arranged that a single plane cannot be passed through them.

Considering the action of these parts 71, 73 and 75, which have just been described, reference is had to Figures 13, 14 and 15. In these figures there is diagrammatically represented in dotted lines the outline of a hat having a relatively sharp "square". The "square" of the hat is the term commonly employed to denote the portion of the hat between the tip and the side walls of the hat. In Figure 15 the iron is shown operating upon the very tip of the hat. The housing or guide 61 for the chain 57 is preferably substantially directly beneath the axis of rotation of the hat. Thus, when the iron is operating upon the tip of the hat, the pull of the weight 32 through the chain 57 is transmitted to the iron through the short arm 76 of the bell crank to the pipe 68 and directly through the arm 56^a to the iron. When the iron is operating the exact tip of the hat the housing 61, the end of the arm 76 and the pipe 68, about which the arm 76 is pivoted, are in a straight line.

As the iron moves in its path of traverse away from the tip of the hat and toward the "square", for example to a position such as shown in Figure 14, the end of the arm 76 tends to swing out of the straight line between the housing 61 and the pivot pipe 68. There is now an arm of force acting upon the bell crank 75-76 tending to swing this bell crank in a clockwise direction as viewed in Figure 14. This force is transmitted through the link 73 and the arm 71 to the spindle 65 and thus tends to swing the iron about the vertical axis of the spindle 65 in a clockwise direction as viewed in Figure 14. When the center of the iron passes over the "square" of the hat, that is after the iron has moved to the left to a slightly greater distance than it has moved in Figure 14, the iron is free to swing about its pivot 65 in a clockwise direction in response to the pull of the weight. However, the iron can swing only until the end of the short arm 76 again comes into the straight line between the pivot 68 and the housing 61.

The iron is thus prevented from suddenly tipping over the "square". The mechanism through which the pull of the weight acts tends to maintain the pull normal to the face of the iron as the iron passes over the "square", this being effected by the tendency of the end of the bell crank arm 76 to remain lined up with the pivot 68 and the chain housing 61. Thus, the iron will move over the "square" of the hat with a gradual tipping or tilting about its axis 65 and all parts of the "square" are thoroughly and properly ironed. There is no possibility of the iron suddenly tilting and thus skipping parts of the hat, and these advantages are achieved regardless of the sharpness of the "square".

In Figure 13 the iron is shown close up to the band of the hat, the band of the hat being the portion thereof substantially at the junction between the brim and crown. It is important that the band portion of the crown be dependably ironed since the ironing gives the felt strength and firmness, and these qualities are particularly desirable at the band, which is required to support the upper portion of the crown. As will be seen from Figure 13, as the iron approaches the band of the hat, there is an arm of force tending to swing the iron about its vertical pivot 65, that is, this arm of force tends to swing inwardly against the hat the portion of the iron which is nearest to the band. Thus, this portion of the iron which approaches closest to the band is urged inwardly against the hat surface with increasing force as the iron approaches the band, and in this manner a thorough and dependable ironing of the band portion is assured.

From the description just given, it will be seen that the ironing tool operates dependably and thoroughly upon all portions of the hat including the difficult "square" and band portion. Uniform results of the ironing are assured regardless of various shapes and styles of hats. The ironing tool will not skip over the "square" but will iron such portion of the hat with the same thoroughness with which it operates upon the remainder and, in addition, the important band portion is particularly well cared for. Preferably the long arm 75 of the bell crank shaped lever is provided with a plurality of holes, as shown in the drawings, so that the force with which the weight tends to tilt the iron may be varied. By moving the connection of the link 73 outwardly along the part 75, the arm of force through which the chain acts is increased. By means of this adjustment the pressure exerted at the band portion of the hat may be varied.

The felt hats which are operated upon by this machine are ordinarily oval in shape. In the manufacture of the hats, the hats are brought to shape from a rough stage by being softened with steam and stretched tightly

over the oval blocks 29 upon which they are ironed and pounced. The softened hat body is generally secured to the hat block by a cord drawn tightly around the band. When the hats are ironed, they are first moistened as by means of a wet sponge or a wet brush. The moistened felt is, at this stage, soft and pliable and the fur fibers are not knitted and shrunk together sufficiently to give the felt the required body and firmness which a finished hat must have. The ironing action is very important. The heat and pressure upon the moistened hat cause the fur fibers to become more tightly felted together and the hat body is given consequent firmness and strength which enable it to hold its shape in use.

When the ironing operation is started, the moistened hat body is soft and limp, and unless proper precautions are taken in ironing, the hat crown may be slipped upon the block out of alinement with the tightly corded band portion, that is, the hat may become twisted on the block. This is very harmful as it weakens the felt and has a tendency to cause the hat to lose its shape after it has been removed from the block. Since the hat is of oval shape, the crown being wider in one dimension than in the other, as the ends of the rotating hat approach the ironing tool, if the hat is rotated about a fixed axis, the hat is required to push the iron outwardly. Then as the ends move away from the iron, the iron follows the hat in. This results in uneven ironing, the ironing pressure applied against two "quarters" of the hat crown being greater than that applied to the other two "quarters". Moreover, the severe rubbing of the iron against the hat as the end portions of the hat approach the iron tends to twist the soft and limp felt and to cause the hat crown to be slipped out of alinement and twisted. These peculiar difficulties met with in ironing felt hats are overcome by the mechanism which will be described hereinafter.

Referring to Figure 17, the iron 31 is mounted upon the supporting member 67 by being swiveled thereon about a horizontal axis 78. This pivotal mounting of the iron eases up the friction and severe action upon the hat as the ends of the hat approach the iron and are required to push the iron outwardly. The iron is permitted to swivel so that it may yield to some extent and permit the "rising quarters" to move thereby more easily. Preferably this swiveling of the iron about the axis 78 is held under control by two light compression springs 79 and 80 bearing against the back of the iron respectively above and below the axis 78. These springs are adjustable by means of screws 81 and 82.

In order wholly and dependably to overcome the danger of uneven ironing and possible twisting of the soft hat body upon the hat block, a mechanism is provided herein for

shifting the axis of rotation of the hat in a direction away from the iron as the ends of the hat approach the iron, and in the opposite direction as the ends of the hat move away from the iron. By means of this mechanism the uneven pressure of the iron against the hat is avoided and there is no binding action or excessive friction at particular points tending to twist the moistened and soft felt about the block.

Referring now to Figure 8, there is shown the shaft 24 having the worm gear 33 thereon and supported in the upper portion of the frame 23. The forward end of this shaft 24 projects through a plate 83 which is rigidly secured to the frame 23 as by means of screws 84. This member 83 has in its front face a horizontal V-way 85 in which is slidably received a coacting part of a circularly shaped member 86. This member 86 has in its front face a circular slot 87 in which is slidably received a segmental shoe 88 (Figure 11). This shoe 88 is mounted by a pin 89 upon the rear face of a rotatable part 90. Between the member 90 and the circular member 86 is a member 91 which is rigidly secured by a pin 92 to the forward end of the shaft 24 and which has on its forward face a V-way 93. In this V-way 93 the part 90 is slidably supported. The pin 89 carrying the shoe 88 projects through an elongated radial slot 94 (Figure 10) in the part 93. The member 90 carries the hot block supporting mechanism, as will be described presently, and thus all movements of the part 90 are given to the hat block and the hat carried thereby.

The parts just described are shown in the drawings as being on center, that is in such position that rotation of the shaft 24 imparts a simple circular movement to the part 90 and the hat block. The drive is transmitted from the shaft 24 to the part 91 and thence to the part 90, the shoe 88 sliding in the circular groove 87. If the circular part 86 is moved in its V-way 85 during rotation of the part 90, the shoe 88 and its connection with the part 90 causes a movement of this latter part in its V-way 93 and a consequent shifting of the axis of rotation of the hat block.

As shown in Figure 10, there is connected to the circular member 86 a rod 95 which projects outwardly through the enclosing casing 96 and by means of which the part 86 may be shifted in its V-way 85 as desired.

Referring now to Figures 2 and 5, there is shown the rod 95 projecting from the casing 96 and pivoted at its outer end 97 to a lever 98. This lever 98 is pivoted at 99 upon a fixed bracket 100 and is connected at its lower end by a link 101 to one arm of a small bell crank lever 102. The bell crank lever 102 is pivoted at 103 upon the frame and its other arm is pivotally connected at 104 with a ver-

tically movable member 105 which rests at its lower end against a roller 106.

Referring now to Figure 2, the roller 106 is carried at the forward end of a lever 107 which is pivoted at 108 in a suitable support in the top of the table 20. At its other end the lever 107 curves upwardly adjacent to the worm wheel 34 and carries at its extreme end a roller 109 which engages the surface of a cam 110 carried upon the face of the worm wheel. The cam 110, rotating with the worm wheel 34, is adapted to swing the lever 107 about its pivot 108 and thus raise and lower the roller 106 at the front end of the lever. Raising of the roller 106 raises the part 105 and this movement, transmitted through the bell crank 102, the link 101, and the lever 98, forces the rod 95 inwardly and thus shifts the position of the circular cam plate 86. Preferably the lever 98 is provided with a plurality of openings 98a to any one of which the link 101 may be connected. By moving the link 101 along the lever 98 an adjustment is effected of the distance through which the circular cam plate 86 will move in response to a given movement of the roller 106.

As shown in Figures 10-12, on the side of the circular cam plate 86 opposite to the rod 95 is secured a rod 111 which projects through the casing 96 and has coiled thereabout, between the casing and an adjusting nut 112, a compression spring 113. This spring 113 acts against the inward movement of the rod 95 and, when the roller 106 drops, this spring causes the linkage to follow the movements of the roller. Also, this spring steadies the action of the parts and takes up any play at the connections and pivots.

As the cam 110 rotates with the worm wheel 34, it acts upon the lever 107 to shift the circular cam plate 86 back and forth in its horizontal V-way 85. This cam 110 is so shaped that the highest parts thereof 110^a and 110^b move the circular cam plate 86 from its position on center through a distance substantially equal to one-half the difference between the major and minor axes of the oval of the hat adjacent the band. It will be apparent that various sections taken parallel to the brim of the hat at various points between the tip and the brim vary in oval outline. The oval becomes gradually more pronounced in sections taken successively from the tip toward the band.

The cam 110 is so positioned upon the worm wheel 34 and so related thereon to the connection between the crank arm 40 and the worm wheel that the high surface 110^a contacts the roller 109 when the iron is operating adjacent to the band on one side of the hat, and so that the surface 110^b acts upon the roller 109 when the iron is operating near the band on the opposite side of the hat or at the opposite end of its traverse.

Between the two surfaces 110^a and 110^b the radius of the cam gradually decreases, and the lowest surfaces 110^c and 110^d thereof engage the roller 109 when the iron is operating upon the tip of the hat. At this point no correction for the oval is required or desirable, and the surfaces 110^c and 110^d are of such height that the circular cam plate 86 is held thereby substantially on center.

From the above it will be seen that, as the iron operates upon the hat adjacent to the band, the oval movement of the hat or the shifting of the axis of rotation thereof is at a maximum; as the iron moves away from the band and toward the tip the oval action is gradually decreased until, when the iron crosses the tip, there is substantially no shifting of the axis of rotation of the hat; then as the iron moves away from the tip and again toward the band, the oval action is gradually increased. The result is as though the iron were operating continually upon a substantially circular surface 25 rotating about a fixed axis. The iron is not required to move in and out to accommodate the oval shape of the hat and the harmful straining of the felt caused by uneven pressure and excessive friction is wholly avoided.

Preferably in order to adapt the cam 110 for use in ironing various styles of hats, the cam is made with a wide face and the roller 109 is adjustable in the lever 107 to coact with different portions of the cam surface. This construction is brought out more clearly in Figure 4. For example, the surface of the cam adjacent to the edge 110^e is suitable for a shape of hat that is very sharp at 40 the "square", having a flat top crown, and the portion of the cam adjacent the edge 110^f is suitable for the other extreme style or what is known as a hat "full round" at the "square". The portions of the cam surfaces between the edges 110^e and 110^f are adapted for styles between these two extremes. As shown in Figure 4, the roller 109 is carried in the end of the lever 107 by a spindle 114 upon which it is threaded 50 for adjustment transversely of the cam surface.

As shown in Figure 2, the cam 110 is secured to the face of the worm wheel 34 by means of bolts 115 and 116 passing through 55 segmental slots in the cam. By loosening these bolts 115 and 116 and turning the cam upon the worm wheel the cam may be adjusted into the exactly proper relation to the connection between the crank arm 40 and the worm wheel. This adjustment is important in insuring that the maximum oval action occurs when the iron is operating upon the hat adjacent the band. This relation, once established, is permanent and is not affected 60 by other adjustments of the machine.

As has been mentioned above, by adjusting the connection of the crank arm 40 with the worm wheel 34 by means of the bolt 41 and the radial slot 42 (Figure 6), the length of the reciprocations of the rack 45 is adjusted and hence the length of the path of traverse of the iron is adjusted. This connection may be so adjusted that the iron will travel from the band of the hat to the tip and then return to its starting point on 75 the same side of the hat; or the connection may be so adjusted that the iron will travel from the band on one side, across the tip, to the band upon the opposite side and then return. The adjustment between the bracket 44 (Figure 6) and the rack 45, by means of the set screws 46, determines the locus of the path of travel of the iron across the hat, that is, it determines between what two points the iron will move for a given length 80 of traverse. Preferably in operation this adjustment of the bracket 44 upon the rack 45 is made such that the iron moves close up to the band of the hat each time it approaches the band.

The iron 31 is preferably heated by an electric heating unit 120 positioned upon the back of the iron as shown in Figure 17. As shown in Figure 2, the wires 121 for leading current to the heating element pass upwardly 85 through the pipe 68 and thence down through the iron supporting member 67. If desired, the iron may be heated by gas, an arrangement of piping being employed such as that shown in Figure 7. A gas pipe 122 and an 100 air pipe 123 lead into a pipe 124 which passes upwardly through the pipe 68 and thence downwardly, terminating in a device 125 having a plurality of holes therein positioned to direct the gas flame against the iron.

When electricity is employed to heat the ironing tool 31, the flow of current to the iron and hence the temperature to which the iron is heated is preferably controlled by a rheostat 126, shown in Figures 2 and 3a. The 110 wires leading from a source of current supply are shown at 127 entering a casing 128 secured to the bottom of the table 20. These wires lead to a switch 129 which controls the flow of current both to the motor 25 and 115 through the rheostat 126 to the ironing tool. This switch 129 is preferably so constructed that, upon the first turn of the switch the circuit is completed to the heating element of the iron; on the second turn of the switch the connection to the heating element remains closed and the circuit of the motor 25 is closed so that the motor starts operation; on the third turn of the switch, the circuit of the heating element is broken and the circuit of the motor is left closed; a further turn of the switch shuts off the motor. With this arrangement, the operator may give the switch one turn to heat up the tool before the operation of the machine is started. Another turn 130

of the switch starts the machine, and a third turn of the switch stops the heating of the tool while the machine continues to run, thereby avoiding danger of over-heating the tool and burning the hat.

Referring to Figures 3a and 3b, the construction of this switch 129 is shown more clearly. It comprises preferably a stationary element and a rotatable element. The stationary element comprises three contacts 150, 151 and 152, and the movable or rotatable element consists of a metal member having three arms 153, 154 and 155. Connected to the contact 150 is a wire 127a leading from the source of current; the contact 151 is connected by a wire 156 to the motor 25; and the contact 152 is connected by a wire 121a to the heating element of the iron. In Figure 3b, the rotatable member of the switch is shown in four different positions A, B, C and D. In the position A, the arm 154 engages the contact 152 and the arm 155 engages the contact 150; thus the circuit of the heating element of the iron is closed but the circuit of the motor is open and the motor remains stationary. A 90° turn of the switch in the direction indicated by the arrow moves the parts from the position A to the position B. In the position B the arm 155 engages the contact 151, the arm 153 engages the contact 152, and the arm 154 engages the contact 150; thus, both the circuit of the heater element and the circuit of the motor are closed. A further turn of the switch in the same direction through 90° moves the parts from the position B to the position C. In the position C the arm 154 engages the contact 151 and the arm 153 engages the contact 150; thus, the motor circuit remains closed while the circuit of the heater element is opened. A further turn of the switch in the same direction through 90° more moves the parts from the position C to the position D. In the position D none of the three arms of the switch is in engagement with the contact 150 and hence both the circuit of the motor and the circuit of the heater element are open.

This switch construction is of distinct advantage when the ironing machine is employed, for example, in a hat renovating business where the machine is used only intermittently. When the operator has a hat or two to be ironed, he gives the switch one turn to start heating the ironing tool while he is engaged in some other work. When the iron is sufficiently hot, by giving the switch a second turn the motor is started and the iron continues to heat. After the hat is ironed sufficiently it does not harm to iron it further but, in fact, the more ironing the hat receives the better the results achieved, providing the iron does not over-heat and burn the felt. The operator may give the switch a third turn which shuts off the heating element while permitting the motor to still drive the machine.

Considering now more particularly the manner in which the hat block 29 is supported for rotation, reference is had particularly to Figure 8. As shown in this figure, the rotatable member 90 has secured to the center thereof as by a screw 130, an outwardly projecting shaft or spindle 131, the end portion of which is adapted to enter the central recess in the hub of the hat block and center the hat block. The member 90 has also a forwardly projecting hub 132 is exteriorly threaded. This hub is provided with a plurality of radial slots 133, preferably three in number, in each of which is a forwardly projecting jaw 134 which is pivoted to the hub 132 at its rear end 135. Upon the exterior of the hub 132 is threaded a collar 136 having suitable means such as a plurality of handles 137 by means of which it may be threaded along the hub 132. Each of the jaws 134 has an inclined surface 138 which bears outwardly in a radial direction against the front edge of the collar 136 under the urge of a leaf spring 139.

The jaws 134 are adapted to grip the hub of the hat block as is shown in Figures 2 and 6. By turning the collar 136 so as to thread it forwardly, the jaws are urged inwardly to grip the hub of the hat block; when the collar is threaded in the opposite direction the springs 139 are permitted to release the grip of the jaws. Preferably there is mounted upon the collar 136 a plate 140 which rubs against the front face of the casing 96 and prevents the access of dirt or dust to the mechanism within the casing.

The jaws 134 project through radial slots in a face plate 141 which is mounted to rotate with the spindle 131 and the jaws. This face plate is shown fitted upon the reduced forward end portion of the spindle 131 and secured to the hub 132 as by screws 142. When a hat block is placed in position upon the machine, the spindle 131 is registered with the central opening in the hub and the block is shoved in until the bottom thereof comes against the face plate 141. Thereupon, the collar 136 is advanced to tighten the jaws 134 upon the hub. It will be seen that the hat block is securely held and that it may be placed in position and removed with the greatest convenience. The shaft 24 rotates but slowly, and the hat blocks may be placed upon the machine and removed while the machine continues to run.

Referring to Figures 8 and 9, projecting from the front of the face plate 141 is a positioning pin 143. This pin is adapted to enter a hole in the base of the hat block which is generally positioned near the edge of the block and on the line of the major axis of the oval hat. This pin thus serves to position the oval hat in proper angular relation to the oval action mechanism contained within the casing 96 and previously described. In order that this positioning may always be achieved

accurately, the pin 143 is preferably adjustable in position throughout a small arc. The pin passes through a slot 144 and has a shoulder which engages the front surface of the face plate, a nut 145 being threaded upon the rear end thereof. By loosening the nut 145 the position of the pin 143 in the slot may be adjusted. Preferably the face plate is graduated as shown at 146 in Figure 9 to aid in this adjustment.

The great majority of hat blocks are "scoped" on the bottom, that is, the bottom edges of the hat block are higher at the sides than they are at the ends of the hat. This "scope" of the hat block is shown in Figures 2 and 6. Because of this "scope", when the hat block is pushed up against the face plate 141 the ends of the block contact the face plate and the sides are spaced outwardly therefrom. This gives only two-point bearing of the hat block against the face plate and tends to make the mounting of the hat block upon the machine somewhat unsteady. In order to overcome this difficulty, as shown in Figure 10, there are provided in the face plate 141 a pair of set screws 147 and 148 which are positioned adjacent the edges of the face plate at the points opposite to which the sides of the hat block come. The sides of the bottom surface of the hat block are adapted to rest against the heads of these screws and thus a four-point bearing for the base of the hat block is achieved. This aids greatly in steadyng the movement of the hat and assists in accomplishing uniform ironing. The screws may be adjusted to accommodate various "scopes".

When operating upon hats of unusually low crown, there is a likelihood that the ironing tool 31 will tend to tilt as it passes over the portion of the hat between the tip and the "square". This is because the tip of the hat approaches so closely to the line of the vertical axis about which the arm 52 swings. In order to overcome this difficulty, it is desirable when operating upon hats of unusually low crown to support the hat at a distance outwardly from the face plate 141. This may be accomplished by a suitable collar 131a shown in Figure 10 and in Figure 10a which is slipped over the spindle 131 and up against the face plate 141 and which thus rests between the base of the hat block and the face plate. This collar may be made of any required thickness or there may be employed a number of them as required to properly position the hat. With this provision, the tendency for the iron to begin its tilting action too soon after passing over the tip of the hat is avoided.

From the foregoing it will be seen that there is herein provided a machine which achieves advantages of distinct practical importance. The machine is capable of operating dependably and with consequent uni-

form results upon all grades and styles of hats.

As many possible embodiments may be made of the above invention and as many changes might be made in the embodiment above set forth, it is to be understood that all matter hereinbefore set forth or shown in the accompanying drawings, is to be interpreted as illustrative and not in a limiting sense.

I claim:

1. In a machine of the character described, in combination, means adapted to support and rotate a hat, an ironing tool, means adapted to give said iron a traversing movement across the surface of said rotating hat in a path extending between the band and the tip, means urging said iron against said hat during said traversing movement, and pivoted means coacting with said urging means and adapted as said iron approaches the band of the hat to act positively to cause the portion thereof nearest the band to bear with increased pressure against the hat surface.

2. In a machine of the character described, in combination, means adapted to support and rotate a hat, an ironing tool, means adapted to give said iron a traversing movement across the surface of said rotating hat in a path extending between the band and the tip, means mounting said iron to swing about an axis substantially at right angles to its path of movement, means adapted to urge said iron against said hat during said traversing movement, and movable means providing a variable leverage through which said last means acts adapted as said iron approaches the band of the hat to act positively to swing inwardly toward the hat surface the portion of said iron nearest to the band.

3. In a machine of the character described, in combination, means adapted to support and rotate a hat, an ironing tool, means adapted to give said iron a traversing movement across the surface of said rotating hat in a path extending between the band and the tip, means mounting said iron to swing about an axis substantially at right angles to its path of movement, and means adapted throughout a portion of the range of movement of said iron to hold said iron against swinging about its said axis and adapted as said iron approaches the band of the hat to tend to swing said iron about said axis so as to cause said iron to press firmly against the portion of the hat crown closely adjacent to the band, said last means comprising a weight and a lever pivoted to swing about an axis parallel to said first axis.

4. In a machine of the character described, in combination, means adapted to support and rotate a hat, an ironing tool, means adapted to give said iron a traversing movement across the surface of said rotating hat in a path extending between the band and the tip,

- means mounting said iron to swing about an axis substantially at right angles to its path of movement, and means comprising a lever pivoted to swing about an axis spaced from said first axis and adapted to control the swinging of said iron about said axis and prevent a sudden tipping of the iron as it passes over the "square" of the hat. 5. In a machine of the character described, 10 in combination, means adapted to support and rotate a hat, an ironing tool, means adapted to give said iron a traversing movement across the surface of said rotating hat in a path extending between the band and the tip, means mounting said iron for swinging about an axis substantially at right angles to its path of movement, means urging said iron inwardly against said hat, and pivoted means through which said last means acts 15 adapted to control the swinging of said iron about said axis and prevent a sudden movement of the iron over the "square" of the hat. 6. In a machine of the character described, 20 in combination, means adapted to support and rotate a hat, an ironing tool, means adapted to give said iron a traversing movement across the surface of said rotating hat in a path extending between the band and the tip, and means adapted to urge said iron against the surface of said hat, the force exerted by said means being in a direction substantially normal to the face of the iron when the iron is acting upon the tip of the hat, 25 and said force tending positively to tilt the iron as it approaches the "square" of the hat. 7. In a machine of the character described, 30 in combination, means adapted to support and rotate a hat, an ironing tool, means adapted to give said iron a traversing movement across the surface of said rotating hat in a path extending between the band and the tip, means mounting said iron for swinging about an axis substantially transverse to its 35 path of movement, means urging the iron against the hat surface, and movable means through which said last means acts tending by lever action to maintain said iron in such position about said axis that the force exerted by said last means is normal to the face of the iron as the iron passes over the "square" 40 of the hat. 8. In a machine of the character described, 45 in combination, means adapted to support and rotate a hat, an arm mounted to swivel about an axis adjacent to said hat supporting means, a second arm pivotally connected to said first arm and carried thereby adjacent the outer end thereof, an iron carried by said 50 second arm at a part thereof remote from said pivot, means urging said second arm to swing about its pivot and thereby urging said iron against the crown of said hat, means adapted to turn said first arm about said axis to cause 55 said iron to traverse the surface of said rotating hat in a path extending between the tip and the band, and means urging said 60 second arm to swing about its pivot upon 65 tating hat in a path extending between the tip and the band thereof, said iron being swiveled in said second arm to swing about an axis substantially transverse to its path of movement, and movable means connected to and coacting with said urging means adapted to prevent a sudden tilting of said iron about its said axis as it passes over the "square" of the hat. 70 9. In a machine of the character described, 75 in combination, means adapted to support and rotate a hat, an arm mounted to swivel about an axis adjacent to said hat supporting means, a second arm pivotally connected to said first arm and carried thereby adjacent the outer end thereof, an iron carried by said second arm at a part thereof remote from said pivot, means adapted to turn said first arm about said axis to cause said iron to traverse the surface of said rotating hat in a path extending between the tip and the band, and means urging said second arm to swing about its pivot upon 80 its pivot upon said first arm to hold said iron in against said hat as said traversing movement takes place, said iron being swiveled in said second arm to swing thereon about an axis substantially transverse to its path of traverse, and movable means associated with said last means being adapted to control the swinging of said iron about its said axis to 85 prevent a sudden tipping of the iron as it passes over the "square" of the hat. 10. In a machine of the character described, 90 in combination, means adapted to support and rotate a hat, an ironing tool, means adapted to give said iron a traversing movement across the surface of said rotating hat in a path extending between the band and the tip, means adapted to urge said iron against the surface of said hat during said traversing movement, and pivoted means 95 through which said last means acts adapted throughout a portion of the range of movement of said iron to hold said iron against swinging and adapted as said iron approaches the band of the hat through increased leverage to swing inwardly toward the hat surface the portion of said iron nearest to the band, said last means being adjustable for varying the force with which said portion of the iron 100 is urged against the hat. 11. In a machine of the character described, 105 in combination, means adapted to support and rotate a hat, an arm mounted to swivel about an axis adjacent to said hat supporting means, a second arm pivotally connected to said first arm and carried thereby adjacent the outer end thereof, an iron carried by said second arm at a part thereof remote from said pivot, means adapted to turn 110 said first arm about said axis to cause said iron to traverse the surface of said rotating hat in a path extending between the tip and the band, and means urging said 115 second arm to swing about its pivot upon 120 125 130

said first arm to hold said iron in against said hat as said traversing movement takes place, said iron being swiveled in said second arm to swing thereon about an axis sub-

stantially transverse to its path of traverse; pivoted means through which said last means acts adapted as said iron approaches the band of the hat positively to tilt said iron about its said axis to press the portion of the iron nearest the band with increased force against the hat surface, and means for adjusting said last means to vary the force tending to cause said tilting.

12. In a machine of the character described, in combination, means adapted to support and rotate a hat, an arm mounted to swivel about an axis adjacent to said hat supporting means, a second arm pivotally connected to said first arm and carried thereby by adjacent the outer end thereof, an iron carried by said second arm at a part thereof remote from said pivot, means adapted to turn said first arm about said axis to cause said iron to traverse the surface of said rotating hat in a path extending between the tip and the band, said iron being swiveled in said second arm to swing thereon about an axis substantially transverse to its line of movement, means for urging said iron into engagement with the hat as it traverses the surface thereof, and a movable mechanism mounted upon said second arm adjacent to said iron and through which said last means acts adapted to control the tilting of said iron about its said axis, said mechanism being adapted throughout a portion of the range of movement of the iron to hold the iron against tilting about its said axis and adapted as the iron approaches the band of the hat to tend to swing inwardly toward the hat surface the portion of the iron nearest to the band.

13. In a machine of the character described, in combination, means adapted to support and rotate a hat, an arm mounted to swivel about an axis adjacent to said hat supporting means, a second arm pivotally connected to said first arm and carried thereby by adjacent the outer end thereof, an iron carried by said second arm at a part thereof remote from said pivot, means adapted to turn said first arm about said axis to cause said iron to traverse the surface of said rotating hat in a path extending between the tip and the band, said iron being swiveled in said second arm to swing thereon about an axis substantially transverse to its line of movement, means for urging said iron into engagement with the hat as it traverses the surface thereof, and a movable mechanism mounted upon said second arm adjacent to said iron and through which said last means acts adapted to control the tilting of said iron about its said axis, said mechanism being adapted to prevent a sudden tipping of said iron as it passes over the "square" of the hat and being adapted as

said iron approaches the band of the hat to cause the portion thereof nearest to the band to press with increased force against the hat surface.

14. In a machine of the character described, in combination, means adapted to support and rotate a hat, an ironing tool, means adapted to give said iron a traversing movement across the surface of said rotating hat in a path extending between the tip and the band, means mounting said iron for swinging about an axis substantially lengthwise of its path of movement and substantially midway between its sides, and spring means for resisting and controlling the swinging of said iron about its said axis.

15. In a machine of the character described, in combination, means adapted to support and rotate a hat about a substantially horizontal axis, an ironing tool means adapted to give said iron a traversing movement across the surface of said rotating hat in a substantially horizontal path extending between the band and the tip, means mounting said iron to swivel about a substantially horizontal axis and about a substantially vertical axis as it traverses the hat, spring means for controlling the swiveling of said iron about said first axis, and means for controlling the swiveling of said iron about said second axis to prevent a sudden tipping of said iron as it passes over the "square" of the hat.

16. In a machine of the character described, in combination, means adapted to support an oval hat block having stretched thereover a soft and moistened hat body of felt, means adapted to rotate said support and said hat block and said hat body carried thereby, a heated iron, means urging said heated iron against said hat body, means adapted to give said iron a traversing movement across said rotating hat body in a path extending horizontally from the band on one side across the tip and to the band on the opposite side, means adapted to shift the axis of rotation of said oval hat block during rotation thereof, and means adapted as said iron moves from the band toward the tip on one side of the hat to progressively decrease the distance through which said axis is shifted and adapted as said iron moves from the tip toward the band on the opposite side of the hat to progressively increase the distance through which said axis is shifted.

17. In a machine of the character described, in combination, means adapted to support an oval hat block having stretched thereover a soft and moistened hat body of felt, means adapted to rotate said support and said hat block and said hat body carried thereby, a heated iron, means urging said heated iron against said hat body, means adapted to give said iron a traversing movement across said rotating hat body in a path

- extending horizontally from the band on one side across the tip and to the band on the opposite side, means adapted to shift the axis of rotation of said hat block during rotation thereof, and means adapted as said iron moves from the band to the tip on one side of the hat to gradually decrease the amplitude of said shifting, adapted as said iron crosses the tip to substantially discontinue said shifting and adapted as said iron moves from the tip toward the band on the opposite side of the hat to again start said shifting and gradually increase the amplitude thereof.
- 15 18. In a machine of the character described, in combination, means adapted to support and rotate an oval hat, a heated iron adapted to operate upon the crown of said hat, means adapted to give said tool a traversing movement across said rotating hat in a path extending horizontally from the band on one side across the tip and to the band on the opposite side, means adapted to shift the axis of rotation of said hat during rotation thereof, and a cam for controlling said last means, said cam having a portion adapted to be operative when said tool is moving between the band and the tip on one side of the rotating hat and another portion adapted to be operative when said tool is moving between the band and the tip on the opposite side.
19. In a machine of the character described, in combination, means adapted to support and rotate an oval hat, means adapted to shift the axis of rotation of said hat during rotation, a horizontally slidable member for controlling said last means, a rotating cam, a lever having a part engaging with said cam, said lever being pivoted about a substantially horizontal axis and the end portion thereof being given an up and down movement by said cam, a bell-crank lever operable by the said up-and-down movement of said first lever, and means connecting said bell-crank lever to shift said horizontally slidable member.
20. In a machine of the character described, in combination, means adapted to support and rotate a hat, a tool adapted to operate upon the crown of said hat, a pivoted arm in which said tool is carried, a member in which said arm is pivoted, means adapted to move said member to move said tool in a path of traverse across said hat, means urging said arm to swing about its pivot and thereby urging said tool against said hat and means for holding said arm against the action of said last means in a position in which said tool is out of engagement with said hat, said holding means comprising a pin carried by said arm and means upon said member in which said arm is pivoted adapted to coact with said pin.
21. In a machine of the character de-
- scribed, in combination, means adapted to support a hat, an arm mounted to swing about an axis adjacent to said hat, a tool adapted to operate upon said hat, means mounting said tool upon said arm adapted to permit movement of said tool relative to said arm and toward and away from said hat, means adapted to swing said arm about said axis to give said tool a traversing movement, a flexible member under tension and connected to urge said tool relative to said arm into engagement with said hat, and a housing adjacent said axis through which said flexible member passes, said housing being pivotally mounted and having a part engaged by said flexible member to swing said housing in accordance with the movements of said tool.
22. In a machine of the character described, in combination, means adapted to grip a hat block, means adapted to rotate said gripping means to rotate said hat block, means adapted to enter the central hole in said hat block to center the same for rotation, a plate member about said last means, and adjustable means upon said plate member adapted to be adjusted in a direction lengthwise of the axis of the hat block against which the bottom of said hat block is adapted to bear.
23. In a machine of the character described, in combination, means adapted to support an oval hat block having stretched thereover a soft and moistened hat body of felt, means adapted to rotate said support and said hat block and said hat body carried thereby, a heated iron means for holding said heated iron and the surface of said hat body in engagement, means adapted relatively to move said rotating hat body and said iron to give said iron a traversing movement across said rotating hat body in a path extending horizontally between the brim and the tip, automatic means adapted to move said rotating oval hat block bodily in a direction away from the operative surface of said iron as the ends of said oval hat block approach said iron and to move said rotating hat block bodily toward the operative surface of said iron as said end portions move away from said iron, and automatic means adapted to change the amount of said bodily movement of said hat block as said traversing movement takes place.
24. In a machine of the character described, in combination, means adapted to support and rotate a hat, traversing mechanism rotatable about an axis adjacent said hat support, an iron pivotally supported upon said traversing mechanism and adapted to traverse the surface of said hat, a rock lever pivoted adjacent the support of said iron, means connected to said rock lever urging the iron against the hat surface, and means connecting said iron with said rock lever to enable said urging means, acting

through said rock lever, to tend to keep the iron-faced toward the center of rotation of said traversing mechanism.

25. In a machine of the character described, in combination, means adapted to support and rotate a hat, an ironing tool, means adapted to give said iron a traversing movement across the surface of said rotating hat in a path extending between the tip and the band, means mounting said iron for swinging about an axis substantially lengthwise of its path of movement and substantially midway between its sides, and adjustable spring means for resisting and controlling the swinging of said iron about its said axis.

26. In a machine of the character described, in combination, means adapted rotatably to support a hat, an ironing tool adapted to iron said hat, an electric motor connected to rotate said hat, an electric heating element adapted to heat said iron, a source of current, a circuit connecting said motor with said source of current, a circuit forming a shunt with said first circuit and containing said heating element, means providing three unconnected points of contact, two of which are individual to the said circuits respectively and the other of which is common to said circuits, and a movable contact adapted upon movement in one direction to close the circuit of said heating element, adapted upon further movement in the same direction to close the circuits of both said heating element and said motor, and adapted upon still further movement in the same direction to open the circuit of said heating element and close the circuit of said motor.

27. In a machine of the character described, in combination, means adapted to support and rotate a hat, an ironing tool, mechanism to traverse said ironing tool across the surface of said hat, an arm included in said mechanism which assumes different positions as said iron traverses, a parallel linkage mechanism connected to said arm said parallel linkage mechanism consisting of four members joined at four pivot axes so arranged that a single plane cannot be passed through all of said pivot axes, means supported by one of the members of said parallel linkage mechanism for pivotally supporting said ironing tool, the axis of the pivot for said ironing tool being perpendicular to the axes of the four members of the parallel linkage mechanism and the parallel linkage mechanism serving, in the different positions of the arm, to maintain the face of said ironing tool substantially tangent to the hat, the pivotal mounting for the ironing tool permitting adjustment thereof in a second plane.

28. In a machine of the character described, in combination, means adapted to support and rotate a hat, an ironing tool, an arm mounted on an axis substantially perpen-

dicular to the axis of rotation of the hat, a parallel linkage mechanism supporting the ironing tool from the arm said parallel linkage mechanism consisting of four members joined at four pivot axes so arranged that a single plane cannot be passed through all of said pivot axes, and means acting on the linkage mechanism urging the ironing tool toward the hat and tending to keep the plane of the ironing tool's surface tangent to an arc of movement of the arm.

29. In a machine of the character described, in combination, means adapted to support and rotate a hat, an ironing tool, means adapted to give said ironing tool a traversing movement across the surface of said hat, said means including oscillating mechanism and a single arm pivoted to swing in a horizontal plane actuated by said oscillating mechanism to cause an end portion of said arm to move in a path substantially like the contour of the hat to be ironed, said arm serving to support said ironing tool, and a pair of links pivoted on said end portion of said arm on parallel axes controlling the angular position of said ironing tool, said links in all positions thereof being substantially parallel to each other.

In testimony whereof, I have signed my name to this specification this 11th day of January, 1927.

JAMES F. DORAN.
